Term of patent 14 years

Int. Cl. D23—01

U.S. CL. D23—45

FIG. 1 is a top plan view of a corrugated pipe showing my new design;

FIG. 2 is a side elevational view thereof;

FIG. 3 is a bottom plan view thereof;

FIG. 4 is a bottom plan view of a second embodiment of the corrugated pipe shown in FIG. 1 with the top thereof being the same as shown in FIG. 1;

FIG. 5 is a bottom plan view of a third embodiment of the corrugated pipe shown in FIG. 1 with the top thereof being the same as shown in FIG. 1;

FIG. 6 is a bottom plan view of a fourth embodiment of the corrugated pipe shown in FIG. 1 with the top thereof being the same as shown in FIG. 1;

FIG. 7 is an end view taken from the left of any of the four embodiments;

FIG. 8 is a sectional view taken along line 8—8 of FIG. 3; and

FIG. 9 is a sectional view taken along line 9—9 of FIG. 5.

A portion of the corrugated pipe has been broken away in FIGS. 1, 2, 3, 4 and 5 to indicate indeterminate length.

I claim:

The ornamental design for a corrugated pipe, substantially as shown and described.
